SAILING CRAFT

Thomas M. Russell, Jr., P.O. Box 85,
North Branford, Conn.
Filed Jan. 7, 1959, Ser. No. 785,457
10 Claims. (Cl. 114—39)

The present invention relates to the art of sailing, and particularly to a new and improved integral sailing unit for use with any type of craft and embodying a novel principle which is capable of reducing to a minimum the resistance to motion created by contact between certain forms of crafts and the water within which they are sailing.

There are two different fluids involved in sailing, each having different relative motions. Combining these two relative motions at the point of contact of the fluids permits sailing. The fin, centerboard or keel of a sailing craft provides the means for continuing the motion of the craft through the water in one direction. The rudder is used for varying the direction of the motion, or course. The sail is adjusted relatively to the wind and the desired course to provide the sailing motion. Accordingly, the primary parts of any unit that will sail include a mast, a sail, a fin or centerboard, and a rudder, all interrelated and connected together. The only additional essential element comprises a device to float the preceding listed elements.

One of the principal objects of this invention is to provide an integral sailing unit which may be applied to any float, boat or craft.

Another principal object of this invention is to provide a sailing craft in which the floating device for the above mentioned integral sailing unit provides substantially no resistance to the motion of the craft within water in which it is sailing.

Another object of the invention is to provide such an integral sailing unit in which the rudder is operated independently of the mast and centerboard.

Another object of the invention is to provide such an integral sailing unit in which the floating device can be adjusted angularly with regard to said integral sailing unit.

Another object of the invention is to provide such a craft in which the floating device is journaled on a bearing and may rotate more or less continuously relatively to a platform that is fixed to the mast.

Another object of this invention is to provide a sailing craft having a floating device that will work the craft up into the wind as it proceeds along its course.

Another object of the invention is to provide such a craft in which the floating device rolls on the water in a clockwise or a counterclockwise direction, depending upon whether the craft heels to starboard or to port.

In one aspect of the invention, a mast may have rigidly fixed to it a centerboard, to the latter of which may be pivotally connected a rudder.

In another aspect of the invention, an occupant supporting platform may be rigidly fixed to the mast.

In another aspect of the invention, the occupant supporting platform may be angularly positioned from time to time with regard to the mast.

In a further aspect of the invention, a floating member may be journaled on a bearing surrounding the mast, and a roller may be located between the floating member and the occupant supporting platform to permit relative rotary motion therebetween.

In still another aspect of the invention, an oscillatable shaft may be located within a hollow, longitudinally extending portion of the mast and may include pulley means for supporting lines extending to each side of the rudder. Another pulley means may support other line means, the

2

movement of which may be controlled from the occupant supporting platform. In this way, the position of the rudder may be controlled at the will of the helmsman.

The above as well as other objects and novel features 5 of the invention will become apparent from the following specification and accompanying drawings which are merely exemplary.

In the drawings:

FIG. 1 is an elevational view of a sailing craft to which 10 the principles of the invention have been applied;

FIG. 2 is a sectional view taken substantially along line 2—2 of FIG. 1;

FIG. 3 is a sectional elevational view of another form 15 of sailing craft to which the principles of the invention have been applied;

FIG. 4 is a sectional elevational view taken substantially along line 4—4 of FIG. 3; and

FIG. 5 is a partial plan view, as viewed along line 5—5 of FIG. 3.

20 Referring to the drawings, and particularly to FIGS. 1 and 2, the principles of the invention have been shown as applied to a sailing craft including a mast 10 of any suitable material and a boom 11a, between which an ordinary mainsail 11 may be applied, and which latter may be adjusted by means of mainsheet 11b. The lower portion of the mast 10 may be hollow, for a purpose to be described later.

A fin or centerboard 12 may be fixed to a sleeve 13 slid upwardly over the lower tubular portion of the mast and 30 locked thereto by through pins 14 or the like.

A non-rotary hub 15 may be fixed to the mast 10 between the upper end of the sleeve 13 and a shoulder 16 formed on the mast 10. The hub 15 may include a cylindrical member 17 to which may be fixed flanges 18 and 19.

35 A floatable member 20 may be journaled on the cylindrical member 17 and it may be made of wood, Fiberglas, or any other floatable material, and it may possess any desired peripheral shape although it is preferably a circular disc-like member.

40 An occupant supporting platform 21 of any desired shape may be fixed to the mast 10 and extend along a plane substantially parallel to the plane including member 20. Near the outer end of the platform 21, a roller bearing support 22 may be fixed to its under surface and 45 it may support a roller 23 that rides in contact with the upper surface of the member 20 so that free relative rotary motion may be provided between the member 20 and the support 21.

45 A rudder 24 may be hinged to the fin or centerboard 12 along the outer edge 25 thereof. In order to control the position of the rudder 24 from the occupant supporting platform 21, a bearing support 26 is mounted within the tubular portion of the mast 10, and a vertically disposed, oscillatable shaft 27 is mounted between bearing support 26 and an aligned bearing 28 located along the axis of the mast 10 at the upper end of the tubular portion thereof.

50 A V-groove pulley 29 may be fixed to the shaft 27 and may support within the V-groove thereof a line 30 wrapped around a substantial portion of its periphery and extending through an opening 31 from the interior of the tubular portion of mast 10 to the exterior thereof. Separate strands of line 30 may pass through tubular elements 32 and 33 fixed to opposite sides of the fin or centerboard 12. The elements 32 and 33 are at the same elevation and extend to near the end 25 of the centerboard 12.

55 The rudder 24 may have a bar 34 extending transversely through it for an equal distance on each side thereof. Brace rods 35 may rigidly fix the bar 34 to the rudder 24. The separate strands of line 30 may, respectively,

be connected to the free ends of the bar 34 so that when the shaft 27 is oscillated, the rudder 24 will pivot about the end 25 of the centerboard 12.

Referring to FIG. 1 again, another V-groove pulley 36 may be fixed to shaft 27 near the top thereof, and it may be aligned with a similar V-groove pulley 37 fixed to a shaft 38 that is journaled in a bearing that extends through the occupant supporting platform 21. A tiller 39 may be fixed to the shaft 38 for manipulating the same, and a belt 40 may extend between the pulleys 36 and 37, passing from the interior of the tubular portion of mast 10 through an opening 41 therein.

From the foregoing it is evident that the centerboard prevents rotation of the mast 10 as the wind acts on the sail 11. The direction of movement is governed by the position of the tiller 39, and the member 20 merely rotates on the bearing hub 15 in a direction depending upon whether the craft heels to port or to starboard.

Referring to FIGS. 3, 4 and 5, the principles of the invention are shown as applied to a craft having a hull 50 of usual construction. An opening 51 may be provided in the hull 50, and a tubular sleeve 52 may have an outside diameter to snugly fit the opening 51 and to be joined to the hull in a manner to prevent leakage of water into the hull between the outside of the sleeve 52 and the opening 51. The sleeve 52 may extend upwardly through a support 53 and a flange 54 on the top of sleeve 52 may be fixed to the support 53, thereby providing a substantially vertical tubular bearing, opening from the inside to the outside of the hull 50.

A mast 55 may extend downwardly through the sleeve 52 a substantial distance beneath the hull 50 and it may include a boss 56 adapted to rest on, and form a thrust bearing with, the top of the flange 54 for the mast 55. A mainsail 57 may be attached to the mast 55 in the usual manner.

A sleeve 58 may be fixed to the bottom of the mast 55 in the same way that the sleeve 13 is fixed to the mast 10 of FIG. 1. Also, a fin 59 having a hinged rudder 60 may be fixed to the sleeve 58 in the same way that fin 12 is fixed to the sleeve 13.

The lower portion of the mast 55 may be provided with a vertically extending chamber 61, within which a vertical shaft 62 may be journaled. The shaft 62 may have fixed to it a grooved pulley 63 around which may extend a line 64. The two spaced, parallel portions of line 64 may pass over pulley means 65 having an axis of rotation at right angles to the axis of shaft 62. Other pulley means 66 may be provided for directing the reaches of the line 64 rearwardly of the hull 50 to a pulley 67 fixed to the bottom of a shaft 68, to the top of the latter of which a tiller 69 may be fixed.

Another line 70 may extend from the rudder 60 to a pulley on the lower end of shaft 62 in the same way that line 30 extends from rudder 24 to the pulley 29 in FIG. 1.

The construction and arrangement may be such that oscillation of the tiller 69 will be transferred to the shaft 62 within the chamber 61 of the mast 55, and hence oscillate the rudder 60.

Referring to FIGS. 3 and 5, an arm 71 may be fixed to the mast 55 and it may be provided with a removable detent 72 that may be inserted within any of a plurality of holes 73 arranged in an arc on a top portion of a housing 74 encasing the pulley means 65 and 66.

Although the various features of the improved sailing craft have been shown and described in detail to fully disclose two embodiments of the invention, it will be evident that numerous changes can be made in such details, and certain features may be used without others without departing from the principles of the invention.

What is claimed is:

1. A sailing craft comprising in combination, a mast; a fin fixed to said mast; a rudder pivotally connected to said mast; an occupant supporting platform fixed to said mast; and a float between said fin and support and rotatable about said mast.

2. A sailing craft comprising in combination, a mast; a fin fixed to said mast; a rudder pivotally connected to said mast; an occupant supporting platform fixed to said mast; a float between said fin and support and rotatable about said mast; and means for operating said rudder from said platform.

15 3. A sailing craft comprising in combination, a mast; a fin fixed to said mast; a rudder pivoted to said fin; an occupant supporting platform fixed to said mast; and a float between said fin and support and rotatable about said mast.

20 4. A sailing craft comprising in combination, a mast; a fin fixed to said mast; a rudder pivoted to said fin; an occupant supporting platform fixed to said mast; a float between said fin and support and rotatable about said mast; and means for operating said rudder from said platform.

25 5. For use with a sailing craft, the combination comprising a mast; a fin integrally connected to said mast independently of a floatable object to which said combination is adapted to be applied; a rudder pivotally connected to said fin; an oscillatable shaft within a hollow portion of said mast; motion transmitting means connecting said shaft to said rudder; and means for oscillating said shaft.

30 6. In combination, a hull; a mast extending through said hull and journaled in a bearing within said hull; a fin integrally connected to said mast independently of said hull; and a rudder pivotally connected to said fin.

35 7. In combination, a hull; a mast extending through said hull and journaled in a bearing within said hull; a fin integrally connected to said mast independently of said hull; a rudder pivotally connected to said fin; and means for adjusting said mast, fin and rudder angularly relatively to said hull.

40 8. In combination, a hull; a mast extending through said hull and journaled in a bearing within said hull; a fin integrally connected to said mast independently of said hull; a rudder pivotally connected to said fin; and means for operating said rudder from a tiller within said hull.

45 9. In combination, a hull; a mast extending through said hull and journaled in a bearing within said hull; a fin integrally connected to said mast independently of said hull; a rudder pivotally connected to said fin; means for adjusting said mast, fin and rudder angularly relatively to said hull; and means for operating said rudder from a tiller within said hull.

50 10. In combination, a floatable means; a mast extending from said floatable means and journaled in a bearing supported by said floatable means; a fin integrally connected to said mast independently of said floatable means; a rudder pivotally connected to said fin; and means for adjusting said mast, fin and rudder angularly relatively to said floatable means.
